HAIR WAVER

Lucynda I. Fink, Liscomb, Iowa

Application August 28, 1946, Serial No. 693,432

4 Claims. (Cl. 132—38)

1

This invention relates to a hair waving device which is a modification of the hair waving apparatus of my Patent No. 2,309,638.

The hair waving apparatus of my Patent No. 2,309,638 is for use in waving hair by the heat method, and comprises a base member adapted to embrace the head and having a longitudinal, transversely curved groove to receive the strands of hair, the groove being provided with a series of spaced longitudinal slots therein, a hair positioner disposed within the groove of the base member and having a transverse contour corresponding to the contour of the groove, vertical rows of teeth projecting from said hair positioner adapted to penetrate the strands of hair and enter the slots of the base member, a heating member covering said positioner, and a cover disposed over the heating member.

In the hair waving device according to the present invention the heating member and the cover therefor are eliminated, the base member and the hair positioner adapted to be carried by the latter constituting the basic structure.

Accordingly, an object of the present invention is to provide a hair waving device which enables the waving of hair by the cold method.

Another object of the present invention is to provide a hair waving device wherein the hair positioning members are slidably mounted upon the base member.

A further object of the invention is to provide a hair waving device which is of a simplified structure, and which is easy to operate.

Other objects and advantages will become apparent from the following description:

An embodiment of the invention is illustrated by way of example in the accompanying drawings, wherein:

Figure 1 is a side elevational view of the waving device in assembled relation when in use.

Figure 2 is a fragmentary perspective view of the hair waving device in disassembled relation.

Figure 3 is a top plan view of the waving device of Figure 1.

Figure 4 is a fragmentary elevational view, in section, of a portion of the hair waving device when in assembled relation for use.

Figure 5 is a fragmentary elevational view showing the arrangement of the vertical spaced rows of a pair of hair positioning members when in hair waving position.

Referring to the drawings, numeral 1 designates a vertical post which is attached to the back of a chair 2 by a bracket 3. A T-union 4 is attached to the upper end of the post 1, and

2

slidably mounted in the union is a horizontal rod 5 which is secured in its adjusted position by a wing screw 6. A semi-circular collar 7 is attached to the outer end of the rod 5, which collar is adapted to embrace the neck of the customer who is seated in the chair, and a strap 8 is adjusted around the front of the neck, the strap being attached to the collar 7. A head band 9 is designed to fit over the forehead of the person and has depending portions 10 extending down the sides of the head which portions are connected with the collar 7. The foregoing construction serves to hold the head of the customer in proper position and also as a support for the hair waving devices of the present invention which are detachably connected to the portions 10 of the band 9, as clearly shown in Figures 1 and 3.

The hair waving device of the present invention comprises a supporting bar 11 having a plurality of longitudinally-curved tines 12 arranged in superposed spaced relation and connected to an end of said bar, the tines being adapted to embrace the head. Interposed between the tines 12 and mounted for swinging movement about said supporting bar 11 are longitudinally-curved cover elements 13, each element being provided with a longitudinally-extending slot 14. As shown on the drawings there are two slots 14 in each cover element 13, although only one such slot could be employed.

Positioned or arranged underneath each of the cover elements 13 and slidably mounted on the latter is a longitudinally-curved hair positioning member 15, each of the members 15 having a series of spaced, vertical, transversely-curved rows of teeth 16 projecting from its under surface, the rows of teeth being adapted to penetrate the strands of hair. Projecting from the outer surface of each of said members are a pair of spaced pins 17, the pins extending through the respective slots 14 of the cover element 13, complementary thereto. The pins 17 are secured to the cover element 13 by means of a fastening means or wing nuts 18 to thereby adjustably lock the positioning member 15 to the cover element 13.

Mounted for swinging movement about the top of the supporting bar 11 is a longitudinally-curved sheathing 19 which is adapted to embrace the tine complementary thereto to thereby form a locking means for the strand of hair held therebetween. Projecting from a side edge of each of the cover elements 13 is a lug 20. The lug 20 of the cover element 13 complementary to the sheathing 19 embraces a portion of the latter when such cover element is moved to a position.

of engagement therewith, while the lugs 20 of the other cover elements 13 embrace the tines 12 complementary thereto when the latter elements have been moved to a position of engagement therewith to thereby rigidly retain the tines and cover elements in assembled relation.

In operation, the supporting bar 11 carrying the plurality of curved tines 12 is positioned around the top of the head. The strands of hair are then passed over the uppermost tine 12, whereupon the sheathing 19 is swung to a position such as to embrace the tine complementary thereto to thereby form a locking means for the strand of hair held therebetween. The cover element 13 carrying a hair positioning member 15 which is adjacent the sheathing 19 is then swung to a position such that the rows of teeth 16 projecting from the under surface of the positioning member penetrate the strands of hair. Next, the strands of hair are passed over the tine below, and adjacent to the thus positioned sheathing, and then the cover element carrying a hair positioning member complementary to the latter tine is swung to a position such that the rows of teeth penetrate the strands of hair. The foregoing is shown in Figure 4. The strands of hair are then passed over the other tines in turn with the cover elements swung into position, as above described. With the cover elements and tines thus positioned, the uppermost positioning member 15 of the cover element 13 is shifted so that the pins 17 are at the extreme left of the slots 14, whereupon the wing nuts 18 are turned down to lock the positioning member in its adjusted position. Next, the positioning member of the cover member directly below the uppermost member is shifted so that the pins 17 are at the extreme right of the slots 16, and the wing nuts are tightened. This alternate positioning of the positioning members is continued until all of such members in the series have moved to their required positions. In other words, the respective hair positioning members are moved to positions such that their projecting pins and wing nuts are as shown in Figure 1. The alternate positioning of the respective hair positioning members causes the vertical rows of teeth to be curved in opposite directions, thereby forming undulations in the hair running alternately in opposite directions.

Having thus described my invention I claim:

1. A hair waving device comprising a supporting bar, a plurality of longitudinally-curved tines arranged in superposed, spaced relation and connected to an end of said bar adapted to embrace the head, longitudinally-curved cover elements interposed between said tines and mounted for swinging movement about said supporting bar, each element being provided with a longitudinally-extending slot, a longitudinally curved hair-positioning member arranged underneath each of said cover elements and slidably mounted on the latter, each of said members having a series of spaced, vertical transversely-curved rows of teeth projecting from its under surface adapted to penetrate the strands of hair, a pin projecting from the outer surface of each of said members, said pin extending through the slot of the cover element complementary thereto, and means for securing the pin to said cover element to thereby lock the positioning member to the cover element.

2. A hair waving device comprising a supporting bar, a plurality of longitudinally-curved tines arranged in superposed, spaced relation and

connected to an end of said bar adapted to embrace the head, longitudinally-curved cover elements interposed between said tines and mounted for swinging movement about said supporting bar, each element being provided with a longitudinally-extending slot, a longitudinally-curved hair-positioning member arranged underneath each of said cover elements and slidably mounted on the latter, each of said members having a series of spaced, vertical transversely-curved rows of teeth projecting from its under surface adapted to penetrate the strands of hair, a pin projecting from the outer surface of each of said members, said pin extending through the slot of the cover element complementary thereto, means for securing the pin to said cover element to thereby lock the positioning member to this cover element, and a longitudinally-curved sheathing mounted for swinging movement about the top of said supporting bar adapted to embrace the tine complementary thereto to thereby form a locking means for the strand of hair held therebetween.

3. A hair waving device comprising a supporting bar, a plurality of longitudinally-curved tines arranged in superposed, spaced relation and connected to an end of said bar adapted to embrace the head, longitudinally-curved cover elements interposed between said tines and mounted for swinging movement about said supporting bar, each element being provided with a longitudinally-extending slot, a longitudinally-curved hair-positioning member arranged underneath each of said cover elements and slidably mounted on the latter, each of said members having a series of spaced, vertical transversely-curved rows of teeth projecting from its under surface adapted to penetrate the strands of hair, a pin projecting from the outer surface of each of said members, said pin extending through the slot of the cover element complementary thereto, means for securing the pin to said cover element to thereby lock the positioning member to the cover element, and a lug projecting from a side edge of each of said cover elements adapted to embrace the tine complementary thereto when said cover elements have been moved to a position of engagement therewith to thereby rigidly retain the tines and cover elements in assembled relation.

4. A hair waving device comprising a supporting bar, a plurality of longitudinally-curved tines arranged in superposed, spaced relation and connected to an end of said bar adapted to embrace the head, longitudinally-curved cover elements interposed between said tines and mounted for swinging movement about said supporting bar, each element being provided with a longitudinally-extending slot, a longitudinally-curved hair-positioning member arranged underneath each of said cover elements and slidably mounted on the latter, each of said members having a series of spaced, vertical transversely-curved rows of teeth projecting from its under surface adapted to penetrate the strands of hair, a pin projecting from the outer surface of each of said members, said pin extending through the slot of the cover element complementary thereto, means for securing the pin to said cover element to thereby lock the positioning member to the cover element, a longitudinally-curved sheathing mounted for swinging movement about the top of said supporting bar adapted to embrace the tine complementary thereto to thereby form a locking means for the strand of hair held there-

between, and a lug projecting from a side edge of each of said cover elements, the lug of the cover element complementary to said sheathing embracing a portion of said sheathing when the cover element is moved to a position of engagement therewith, the lugs of the other of said cover elements embracing the tines complementary thereto when the cover elements have been moved to a position of engagement therewith to thereby rigidly retain the tines and cover elements in assembled relation. 10
